UNITED STATES PATENT OFFICE.

LEWIS SAIGER AND MARKS RUSSELL, OF JOHNSTOWN, NEW YORK.

HOLDER FOR THERMOS BOTTLES AND THE LIKE.

Application filed November 24, 1924. Serial No. 751,972.

To all whom it may concern:

- Be it known that we, LEWIS SAIGER and MARKS RUSSELL, citizens of the United States, and residents of Johnstown, in the 5 county of Fulton and State of New York, have invented certain new and useful Improvements in Holders for Thermos Bottles and the like, of which the following is a specification.
- 10 Our present invention relates generally to holders for thermos bottles and the like, our object being the provision of a simple inexpensive device which may be readily mounted in any suitable place for the support of
- 15 a thermos bottle and the like in upright position and in such manner that it may be fully protected and yet remain in view at all times without necessitating the opening of the holder for this purpose.
- 20 A further object is the provision of a holder with simple means for supporting the parts in the closed position, the said parts permitting the holder to be easily and quickly opened whereby the thermos bottle may
- 25 be easily removed.

In the accompanying drawing which illustrates our present invention and forms a part of this specification,

30 Figure 1 is a perspective view showing one of the many practical applications of our invention,

Figure 2 is a vertical sectional view taken through the holder, and

35 Figure 3 is a horizontal section taken therethrough.

Referring now to these figures our invention proposes a holder consisting of a cylindrical slatted frame including two semicylindrical slatted sections 10 and 11, the latter adapted to fit within the former. These sections 10 and 11 have spaced apart slats forming the walls thereof and connected at their ends to end plates 12 and 13, these end plates being of circular form.

40 The section 11 is of somewhat reduced length as compared to the section 10 and its end plates 13 are disposed in coaxial relation with and slightly spaced from the inner surfaces of the larger end plates 12 of section 10, there being axially disposed means consisting of bearing pins 14 and plates 15

45 whereby these end plates are axially connected in order that the inner section 11 may revolve within the outer section 10. For this

purpose the bearing plates 15 are secured to the outer surfaces of the ends 13 of section 11 and the bearing pins 14 are threaded axially through the ends 12 of the outer section 10 and have inner tapering extremities engaging the bearing plates 15.

Thus by revolving the inner section 11 until its slatted semicylindrical wall is within the semicylindrical wall of section 10, the holder is opened for the reception of a thermos bottle and the like 16 within the inner section 11. In this position the thermos bottle will rest upon the lower end plate 13 of the inner section 11, the upper end plate 13 preferably having a flat spring member 17 adapted to engage the top of the thermos bottle and normally prevent the latter from vertical shifting movement. With the thermos bottle within the inner section 11 it is simply necessary to revolve the same until its semicylindrical wall extends across the open side of the outer section 10 as seen in Figure 3, the holder being then closed.

50 In order to secure the holder in closed position, a pivoted spring controlled dog 18 is mounted in connection with a bracket 19 secured upon the lower end plate 12 of the outer section between the ends of its semicylindrical wall, this dog being adapted for extension at its free end between slats of the inner section 11 when the latter is turned to closed position as shown in Figure 3 whereby the holder will thus be locked in the closed position by virtue of the prevention of the inner section from revolving movement until the dog is pressed outwardly against the tension of its controlling spring so as to shift its free end out of engagement with the inner holder section.

55 It is obvious that the holder as thus constructed is adapted to be readily mounted in connection with moving vehicles and the like wherein it may be desired to carry a thermos bottle, and is readily susceptible of mounting upon the running board 20 of an automobile or other motor car 21. It is also obvious that the holder is not only convenient in the respects noted but is simple in construction, inexpensive to manufacture, and may be readily manipulated in use.

60 We claim:

65 A holder of the character described of general cylindrical form including two semicylindrical sections one of which is shiftable

circumferentially within the other, said sections having slatted walls and spaced opposing end pieces of substantially circular form, connections axially of the said end pieces forming the movable pivots of the inner section, article engaging spring means carried by one of the end pieces of the inner section,

and a spring controlled locking dog movably mounted upon one of the end pieces of the outer section and shiftable between slats of the inner section to lock the latter against movement.

LEWIS SAIGER.
MARKS RUSSELL.
